(57) **CLAIM**

We claim the ornamental design for a 2x beam insert, as shown and described.

DESCRIPTION

FIG. 1 is a perspective view of a 2x beam insert showing my new design;

FIG. 2 is a front elevation view of the first embodiment; FIG. 3 is a back elevation view of the first embodiment; FIG. 4 is a left-side elevation view of the first embodiment; FIG. 5 is a right-side elevation view of the first embodiment; FIG. 6 is a top plan view of the first embodiment; FIG. 7 is a bottom plan view of the first embodiment; and, FIG. 8 is a second front elevation view, showing the 2x beam insert placed within a typical beam.

The break lines shown in FIGS. 1-5 and 8 indicate a symbolic break in length. The appearance of any portion of the article between the break lines forms no part of the claimed design.

The broken lines in FIG. 8 depict a typical beam and form no part of the claimed design.
